UNITED STATES PATENT OFFICE.

BENJAMIN ALEXANDER, OF CLEVELAND, OHIO, ASSIGNOR TO THE KAYNEE COMPANY, OF CLEVELAND, OHIO, A CORPORATION OF OHIO.

COMBINED ADVERTISING AND DISPLAYING FIXTURE.

Application filed September 12, 1918. Serial No. 253,729.

To all whom it may concern:

Be it known that I, BENJAMIN ALEXANDER, a citizen of the United States, and a resident of Cleveland, county of Cuyahoga, 5 and State of Ohio, have invented a new and useful Improvement in Combined Advertising and Displaying Fixtures, of which the following is a specification, the principle of the invention being herein explained and 10 the best mode in which I have contemplated applying that principle, so as to distinguish it from other inventions.

The present invention relates to a knock-down type of stand for use in displaying 15 and advertising articles of merchandise for sale. The stand is so constructed that it can readily be taken apart and packed for shipment, and quickly and easily be put together again when desired without the use 20 of tools. Provision is made for holding advertising cards, and these may easily be changed and new cards inserted as desired. To the accomplishment of the foregoing and 25 related ends, said invention, then, consists of the means hereinafter fully described and particularly pointed out in the claims.

The annexed drawing and the following description set forth in detail certain mechanism embodying the invention, such description 30 constituting, however, but one of various mechanical forms in which the principle of the invention may be used.

In said annexed drawings:—

Fig. 1 is a perspective view of the device 35 assembled; Fig. 2 is a section on the line 2—2, Fig. 1, showing the method of construction; Fig. 3 is a section on the line 3—3, Fig. 2; and Fig. 4 is a detail view of the construction of the base member.

As illustrated, the device is a stand having 40 two feet or base members 1, having hollow bosses 2 at their center portions, each boss having a flange 7 at the lower end and having two tapped horizontal apertures 3 and 4, the lower aperture 3 being adapted 45 to receive the threaded ends of a tie rod 6, and the upper aperture 4 receiving set screw 30. Into the hollow bosses are inserted two uprights 8, the uprights being 50 preferably hollow rods, the ends 9 resting on the flanges 7 and being firmly held in the bosses by means of the set screws 30.

The rods 8 are threaded at their upper 55 ends, and internally threaded caps 31 are secured thereto. These caps are of the form

best shown in Fig. 2, and have extending flanges 10 at their sides to receive a cross-bar or rod 11, which will preferably be pressed or brazed into place. Above the rods, the caps have an extending portion 60 which widens out as shown in Fig. 3, to form circular bearing members 12, having two spaced straps 13 connecting the same. Above the upper bearing member the caps terminate in short slabs 14, one being tapped 65 to receive a rod 15, which is adapted to carry a card holder 16.

Within the circular members 12 are mounted two tubes 17 and 18, these tubes having slits 19 and 20, the slits facing each 70 other and being adapted to receive the edges of a display card 21 bearing advertising or descriptive matter.

The card holder 16 is composed of a horizontal strip 22, riveted or otherwise secured 75 to the flattened end 23 of the rod 15. At the outer ends there are attached double spring clips 24, between which the card 25 is held. These clips hold the card in place, and the holder and rod 15 may be removed 80 from the cap or turned at various angles.

Upon the crossbar 11, garment hangers 26 are adapted to be hung, while the cards 21 and 25 will carry appropriate advertising and descriptive matter, referring to the garment 85 or to the line of goods as a whole, or to the store.

It will be seen that the device may be readily taken apart and packed for shipment, and as easily assembled. The only 90 tool necessary is a screw driver for forcing the set screws into engagement with the up-rights.

When taken apart the stand consists of the feet 1, the tie rod 6, the uprights 8, the 95 card rack, comprising the caps, the two split rods and the crossbar 11, and the card holder. These parts, together with the necessary garment hangers 26, can be easily and quickly packed in a small box and readily and 100 quickly assembled at the desired point. The advertising cards will be changed at intervals and the display of garments will be varied or the garments replaced as they are sold.

Other modes of applying the principle of my invention may be employed instead of the one explained, change being made as regards the mechanism herein disclosed, provided the means stated by any of the fol- 110

lowing claims or the equivalent of such stated means be employed.

I therefore particularly point out and distinctly claim as my invention:—

- 5 1. In an advertising fixture adapted to be readily disassembled, the combination of a pair of light metal tubular uprights and a rigid metal frame member adapted to be seated upon the upper ends of said uprights
10 to provide a support for an advertising card, said frame member comprising a pair of socketed and slotted cap members, and a plurality of tubular metal cross-bars, two of said cross-bars being provided with oppositely directed slots each communicating with the slots in said cap members and providing means for the reception of a sheet-like member adapted to bear advertising indicia.

2. In an advertising fixture adapted to be 20 readily disassembled, the combination of base members, light metal tubular uprights adapted to be removably mounted in said base members, a removable tie rod connecting said base members, a rigid frame comprising two cap members and two tie members removably attached to the upper ends of said uprights, the tie members comprising slotted elements having their slotted sides facing one another, slots in said cap members covering the vertical distance between said slots in the tie members, and a long sheet-like member adapted to have its edges engaged in said slots, the sides of said sheet-like member being adapted to carry advertising matter.

Signed by me, this 3rd day of Sept., 1918.

BENJAMIN ALEXANDER.
